UNITED STATES PATENT OFFICE.

MORRIS W. GREENBERG, OF BUFFALO, NEW YORK.

GARMENT-MEASURING DEVICE.

Application filed December 10, 1924. Serial No. 755,068.

This invention relates to a garment measuring device which is more particularly designed for taking measurements of a person for use in making a coat, or similar garment for the same, and it has for its object the provision of a device of this character which will enable a tailor to take accurate measurements of a person for determining the degree of stoop or inclination, the height of shoulders, the "depth of scye", and also other measurements necessary for cutting the parts of the garment preparatory to sewing them together into a finished product.

A further object of this invention is to provide a device of this character whereby these measurements can be taken readily, conveniently, and accurately so that a garment made in accordance with the same will fit the person for whom it is intended without an unnecessary amount of "trying on" as has been the custom heretofore.

Additional objects of this invention are to furnish an apparatus of this character, which is comparatively simple and inexpensive in construction, which can be readily adjusted to the form of the person which is being measured, which permits of taking the several measurements expeditiously and accurately and which can be folded compactly when not required for use and can be manufactured at comparatively low cost.

In the accompanying drawings: Figure 1 is a perspective view of my improved garment measuring device showing the same applied to the back of a person in the manner in which this is done when taking measurements of a person for use in making a coat for the same.

Figure 2 is a horizontal section of the device taken through that part thereof which is utilized for measuring the "depth of scye" of the person, this section being taken on line 2-2, Fig. 6.

Figure 3 is a fragmentary rear elevation of that portion of the device shown in Fig. 2.

Figures 4 and 5 are fragmentary perspective views showing the form of hinge or pivotal connection between the "depth of scye" crossbar and each of the "depth of scye" locating arms.

Figure 6 is a vertical longitudinal section of the garment measuring device embodying

my invention taken centrally through the main upright supporting bar and associated parts. 55

Figure 7 is a horizontal section taken on line 7-7 in Fig. 6, and showing more particularly the parts whereby the measurement for the height of shoulder is taken.

Figure 8 is a fragmentary vertical section taken on line 8-8, Fig. 7.

Figure 9 is a fragmentary section taken on line 9-9, Fig. 6.

Figure 10 is a perspective view of one of the vertically movable slides mounted on the upright supporting bar and adapted to support one of the horizontal crossbars. 65

Figure 11 is a fragmentary rear elevation showing a modified form of the means for moving the sections of a horizontal crossbar relatively to each other and toward and from the upright supporting bar which adjusting mechanism differs somewhat in its details of construction from that shown in Figures 1, 2, 3, 6, and 7 for accomplishing 75 the same purpose.

In the following description similar characters of reference indicate like parts in the several figures of the drawings:

In its general organization this garment measuring device is provided with means for measuring the degree of inclination or stoop of the person for whom a coat is to be made, also means for measuring the shoulder height, and also means for measuring the "depth of scye", and also means for conveniently taking tape measurements of such other parts of the person as may be deemed necessary or desirable to produce an accurate fit of the garment after the same is 90 made up.

The main support of this device consists of an upright bar 15, which is preferably made of flat sheet metal and adapted to be engaged with its lower part against the rear side or back of the person being measured midway between the arms of the same, as shown in Figs. 1 and 6. When thus arranged the relation between the upper end of this upright bar and the center of the back of the neck of the person being measured represents the degree of inclination, stoop, or attitude of the person which is being measured. Means are provided for obtaining

a reading or indication of the amount of such an incline or stoop, which means are so organized that they also serve as part of the means for mounting this apparatus on the person being measured. The preferred construction of this supporting means and inclination measuring device comprises an upright flexible band or strip 16 which is arranged in front of the upright bar 15, and 5 its lower end secured thereto by means of rivets 17, or other suitable means while its upper end is provided with a hook 18 adapted to engage with the upper edge of the collar 19 of the person being measured at 10 the rear central part of the neck of the same where the rear collar button is usually located. When the band 16 is thus applied to the collar of the person, this band follows the curvature of the central part of the back 15 of the person from the collar downwardly to 20 the point of connection between this band and the upright supporting bar so that the extent of upward divergence between this bar and band indicates the degree of angularity between these members and at the same time the several parts of the apparatus 25 are suspended from the collar of the person being measured. In order to obtain a reading as to the degree of inclination or stoop 30 of the back of the person various means may be employed and those shown in the drawings are merely illustrative of means suitable for this purpose. As there shown, 35 these means comprise an indicating rod 20 which is secured at its front end to the upper end of the inclination band 16, and projects rearwardly therefrom through an opening 21 in the upper end of the upright bar 15, a bracket 22 secured to the upper part of the 40 rear side of the upright bar 15, and having a perforation 23 through which the indicating or gage rod 20 passes, and a screw nut 24 arranged between the upper part of bar 15 and the bracket 22 and having a screw threaded 45 engagement with rod 20, but held against longitudinal movement between the bar 15 and the bracket 22. Upon turning the screw nut 24 the gage rod 20 will be moved lengthwise through the bar 15 and relative to the 50 neck of the person being measured and thus permit of holding the upper end of the main supporting bar 15 in an upright position and in a definite relation to the upper end of the hook 18 and inclination band 16, in 55 accordance with the degree of inclination or stoop of the person being measured. To permit of conveniently taking a reading of this relation of the upright bar 15, and the inclination band 16, one or both sides of the inclination gage rod 20 may be provided with a longitudinal row of graduations 25, as shown in Figures 1 and 6, from which the tailor may make notations and subsequently construct his cutting chart or layout 60 accordingly.

The means of measuring the shoulder height comprises a horizontal cross bar which is preferably constructed of two sheet metal sections 26, 27 which are adjustable horizontally relatively to each other and toward and from the main supporting bar 15 and are also capable of vertical adjustment on the upright bar 15, and two shoulder height gage arms 28, 29 which normally project forwardly from the opposite outer ends of the crossbar sections 26, 27, and are adapted to rest on top of the shoulders of the person being measured. Upon raising or lowering this crossbar on the upper part of the upright bar 15 these shoulder height gage arms can be adapted to the height of the shoulders of the person being measured. This shoulder height is preferably determined relative to the location of the rear side of the collar of the person being measured, and a reading of this shoulder height is preferably indicated by the relation of this crossbar to an upright scale or row of graduations 30 arranged on the rear side of the upper part of upright bar 15 and adapted to be traversed by this crossbar. When both the shoulder gage arms 28 and 29 bear against the top of the shoulders then the latter are of the same height and the reading of the scale 30 will represent the height of both shoulders. If, however, only one of the shoulder gage arms should engage with the top of its respective shoulder and the other gage arm be elevated or disengaged from its respective shoulder, this indicates that the height of the shoulders is uneven and the tailor therefore makes a note of the same and adjusts the draft of the garment which is to be cut accordingly.

The shoulder height gage arms are preferably so mounted on the opposite ends of the upper crossbar sections 26 and 27 so that these arms may be shifted from their unfolded operative position, shown by full lines in Fig. 7, to a folded position toward the front side of the crossbar sections, as shown by dotted lines in Fig. 7, for the purpose of rendering the apparatus more compact when this is necessary for storage and shipping purposes. This may be accomplished in various ways, for example, by means of upright pins 31 each of which pivotally connects the rear end of each of the shoulder height gage arms with the outer end of one of the upper crossbar sections, as shown in Fig. 7. While each of these shoulder gage arms is in its operative position the same may be held in place by a suitable holding device which in the present instance consists of an upright clamping bolt 32 mounted on the outer end of each upper crossbar section and adapted to engage the adjacent part of the respective shoulder height gage arm, the latter being provided with a notch 130

33 which receives the shank of this bolt in each other and relatively to the upright bar 15 in unison and also hold the same in whatever position the same may have been adjusted.

Various means may be provided for adjusting the upper crossbar sections horizontally relatively to each other and also vertically on the main supporting bar 15. As shown in Figures 1, 6, 7, and 10, this means may consist of a slide 34 capable of moving vertically on the upper rear side of the upright bar 15 and guided thereon by means of vertical channels 38 arranged at opposite vertical edges thereof and engaging with opposite vertical edges of the upright bar 15, as best shown in Fig. 7. This slide may be held in the various positions into which the same may be adjusted vertically on the bar 15 by a holding or clamping device of any approved form which in the present instance 20 consists of the clamping bolt 36 mounted on the lower part of the slide 34 and passing through a vertical slot 37 on the adjacent part of the bar 15, which clamping means when loose permit the slide 34 and the parts 25 mounted thereon to be raised and lowered freely for adapting the gage arms 28, 29 to the shoulder height and thereupon a tightening of the clamp bolt 36 will hold this part securely in this position to enable the tailor 30 to obtain his reading or notations from the scale 30 and also to observe the manner in which the two gage arms 28 and 29 stand in relation to their respective shoulders.

The inner ends of the two sections 26, 27 35 of the upper crossbar overlap each other and are guided at their upper and lower edges in guide channels 35 arranged on the outer side of slide 34 and these crossbar sections are additionally guided upon each other by providing each of these bars at its inner end with guide hooks 40 which embrace the adjacent part of the other crossbar section, as shown in Figs. 1 and 7.

In order to enable accurate measurements 45 to be made of the shoulder height with ease and facility, the two crossbar sections 26, 27 are moved in unison toward and from each other and relatively to the upright bar 15 which means in the form shown in Figs. 1, 50 6, and 7, consist of an adjusting screw 41 mounted in bearings 42 on the rear side of the slide 34, and provided at its opposite end with right and left hand screw threads 43, 44 which engage with internally threaded lugs 45, 46, projecting rearwardly from the crossbar sections 26, 27. Longitudinal movement of this adjusting screw is prevented by means of a thumb wheel 47 secured thereto between its bearings 42 so that upon 55 turning this adjusting screw by means of the thumb wheel or finger piece 47 the right and left hand screw threads upon opposite ends of the same will cause the two crossbar sections 26, 27 and the gage arms 28, 29 thereon to move simultaneously toward and from

each other and relatively to the upright bar 15 in unison and also hold the same in whatever position the same may have been adjusted.

The means for determining the "depth of scye" of the person being measured comprises a lower horizontal crossbar which is capable of vertical adjustment on the lower part of the upright supporting the bar 15, and is preferably constructed of two sheet metal sections 48, 49 which are adjustable horizontally relatively to each other and to upright bar 15, and two "depth of scye" gage arms 50, 51 which project forwardly from the opposite outer ends of the lower crossbar sections 48, 49 and are adapted to engage respectively with the under sides of the arms of the person being measured. For convenience in storing or transporting this device these gage arms 50, 51 are also mounted on the crossbar sections 48, 49 so as to be foldable relatively to the latter. Suitable means for this purpose consist of an upright pivot pin or pintle 52 passing through corresponding hinge eyes 53, 54 arranged respectively at the rear end of each "depth of scye" gage arm and the outer end of the adjacent lower crossbar section. These gage arms 50, 51 may be locked or held in their operative position by various means. Those shown in Figs. 2, 4, and 5, for this purpose consist of a clamping bolt 55 capable of sliding lengthwise in a slot 56 in the rear part of each "depth of scye" gage arm and into and out of a notch 57 on the adjacent end of the respective lower crossbar. When each clamping bolt 55 thus engages both the slot 56 and the notch 57 and is tightened, the respective gage arm is securely held in its upright forwardly projecting position, as shown by full lines in Fig. 2. Upon loosening this clamping bolt 55 and moving the same forwardly in the slot 56 and out of engagement from the notch 57, this gage arm will be free to be shifted inwardly toward the front side of the respective crossbar section 48, 49, as indicated by dotted lines in Fig. 2, thereby rendering the device very compact and capable of being stowed away in considerably less room than otherwise would be required.

The opposing inner parts of the two crossbar sections 48, 49 overlap and are mounted on the vertical movable slide 58 which is capable of being shifted so as to occupy various positions on the rear side of the bar 15 for the purpose of adapting the "depth of scye" gage arms to the arm pits of the person being measured. The slide 58 for this purpose may be guided by means of channels 59—59 on opposite vertical edges thereof receiving opposite vertical edges of the bar 15, as shown in Fig. 2. Upon raising and lowering this slide, together with the crossbar sections 48, 49 mounted thereon the same traverses the lower part of the vertical scale 61

on the upright bar 15 and thereby enables the tailor to determine the location of the "depth of scye" relative to the collar of the person being measured. This last mentioned 5 slide may be held in its adjusted position by means of a clamping bolt 62 mounted thereon and passing through the vertical slot 63 on the adjacent part of the bar 15. Upon loosening this bolt this slide and the crossbar 10 sections 48 and 49 may be raised and lowered as much as may be required to properly engage the arms 50, 51 with the under side of the arms of the person for determining the "depth of scye", and after such adjustment 15 has been effected these parts may be held in position by tightening the clamping bolt 62. The two lower crossbar sections 48, 49 are guided relatively to each other by engaging the upper and lower edges of the same with the 20 upper and lower channels 64, 65 arranged on the upper and lower edges of the slide 58, and after adjustment these crossbar sections may be locked in their relative position by means of a clamping bolt 66 mounted on the 25 crossbar section 48 and passing through a horizontal longitudinal slot 67 on the crossbar section 49, as best shown in Fig. 2. For the purpose of simultaneously moving the two "depth of scye" gage arms toward and 30 from each other and in unison so as to always maintain the proper relation of these arms relatively to the median line of the body, a shifting device is provided for these crossbar sections and the gage arms mounted 35 thereon which in the present instance consist of a rotary cam 68, which is pivoted on the slide 58 by means of a pin 69 passing through slots 70 and 71 in the crossbar sections 48 and 49, and provided with cam 40 slots 72, 73 which engage with pins 74, 75 mounted respectively on the crossbar sections 48 and 49. Upon loosening the clamping bolt 66 and turning the cam 68 in one direction or the other the crossbar sections 48 and 45 49 and the gage arms 50, 51 mounted thereon will be moved simultaneously toward and from each other in unison and at the same rate and to the same extent so that the two gage arms 50, 51 will also be arranged the 50 same distance from the median line of the body being measured.

On the front part of one of the "depth of scye" arms, for example the right hand arm 55 51, is arranged an upwardly projecting horn or gage plate 76 which is adapted to engage with the lower front part of the right hand arm pit, for the purpose of retaining the "depth of scye" arm in a definite relation thereto. This horn 76 is capable of adjustment horizontally back and forth on the arm 60 51 to suit the right hand arm of the person being measured. This is effected by means of two clamping bolts 77 mounted on the lower part of the gage horn 76 and passing 65 through a longitudinal slot 78 in the arm

51, which bolts are loose when adjustment of the horn 76 is effected, but are tightened for holding this horn in place after the desired position has been attained.

Pivots mounted at its lower end by 70 means of a pin 79 on the gage horn 76 is a measuring tape 80. The upper free part of which may be extended across any suitable part of the body or to any point thereof which may require measurement in order 75 to permit the tailor to properly prepare his chart according to which the garment is to be cut, as shown in Figs. 1 and 6. In the example shown in these figures the tape 80 is passed from the gage horn 76 upwardly 80 along the front side of the right arm and over the corresponding shoulder to the collar point on the central rear part of the collar, which is represented by the hook 18. This is one of the measurements usually 85 taken in preparation for cutting a garment of this character. Obviously other measurements may be taken from the point represented by the pivot 79 across the chest and elsewhere about the body, this being a matter 90 left to the discretion of the tailor and governed by any peculiarities of form of the subject which is being measured.

If desired, the screw adjusting mechanism which is represented in the drawings for 95 moving the upper crossbar sections toward and from each other may also be employed as the means for moving the lower crossbar sections toward and from each other instead of the cam mechanism of which the cam 68 100 forms a part. This cam mechanism may also, if desired, be used not only for adjusting the lower crossbar sections toward and from each other, but the same may also be used instead of the screw mechanism represented in the drawings for adjusting the upper crossbar sections toward and from each other.

In place of either this cam mechanism or this screw mechanism for adjusting the crossbar sections toward and from each other, any other suitable mechanism may be employed which will accomplish this purpose, for example, the mechanism which is shown in Fig. 11. In this last mentioned 110 construction a double armed rock lever 81 is employed, the opposite arms of which are pivotally connected by means of rods on links 82 with the two sections 83—84 of the horizontally adjustable crossbar, which latter may at their outer ends carry either the shoulder height arms or the "depth of scye" arms. This double armed lever 81 is mounted by means of a pivot pin 90 on the slide 85 upon which the crossbar sections 83, 84 115 are mounted for horizontal adjustment relatively to each other and which is also capable of sliding vertically upon the upright supporting bar 15 in the manner indicated with reference to the slides 34, 58. These cross- 120 125 130

bar sections 83, 84 may be held in position after adjustment by means of a clamping bolt 86 passing through corresponding slots 87 in these crossbar sections.

5 This garment measuring device taken as a whole is comparatively simple in construction, considering the functions which it performs. The same can be very quickly adapted to a person's form for taking the measurements thereof. The measurements can be taken accurately and form a reliable basis from which a draft of the garment may be subsequently made preparatory to cutting the cloth. It has no delicate parts which are liable to get out of order. Owing to the manner in which the same can be folded into a compact mass, the same can be readily stored away and also conveniently shipped or transported when required.

10 I claim as my invention:—

1. A garment measuring device comprising an upright bar adapted to engage its lower part with the back of a person being measured, a flexible band connected at its 15 lower end to said upright bar and adapted to have its upper part engage with and assume the curvature of the upper part of the back of said person, and means for measuring the distance between the upper end of 20 said upright bar and said flexible band, comprising a gage rod attached at its inner end to said band and passing at its outer end through said upright bar, a bracket which is arranged on the outer side of said 25 bar and through which said rod passes, and a screw nut having a threaded engagement with said rod and arranged between said 30 bar and bracket.

2. A garment measuring device comprising an upright bar adapted to engage with the back of a person being measured, a horizontal cross bar adjustable vertically on said 35 upright bar, shoulder height arms projecting forwardly from opposite ends of said cross bar and adapted to engage with the top of the shoulders of the person being measured, a pivot connecting the rear end of each of 40 said arms with said cross bar to permit of folding said arms relatively to said cross bar, and means for holding said arm in its 45 unfolded position.

3. A garment measuring device comprising an upright bar adapted to engage with the back of a person being measured, a horizontal cross bar adjustable vertically on said 50 upright bar, shoulder height arms projecting forwardly from opposite ends of said cross bar and adapted to engage with the top of the shoulders of the person being measured, a pivot connecting the rear end of each of 55 said arms with said cross bar to permit of folding said arms relatively to said cross bar, and means for holding said arm in its unfolded position, consisting of a clamping 60

bolt arranged on the cross bar and engaging 65 with the respective arm.

4. A garment measuring device comprising an upright bar adapted to be engaged with the back of a person being measured, a horizontal cross bar adjustable vertically 70 on said upright bar, depth of scye arms projecting forwardly from opposite ends of said cross bar and adapted to engage underneath the arms of the person being measured, and each arm being pivotally connected with said 75 cross bar so as to be foldable relatively thereto.

5. A garment measuring device comprising an upright bar adapted to be engaged with the back of a person being measured, a horizontal cross bar adjustable vertically 80 on said upright bar, depth of scye arms projecting forwardly from opposite ends of said cross bar and adapted to engage underneath the arms of the person being measured, and each arm being pivotally connected with said 85 cross bar so as to be foldable relatively thereto, and means for holding each arm in its operative position relative to said cross 90 bar.

6. A garment measuring device comprising an upright bar adapted to be engaged with the back of a person being measured, a horizontal cross bar adjustable vertically 95 on said upright bar, depth of scye arms projecting forwardly from opposite ends of said cross bar and adapted to engage underneath the arms of the person being measured, and each arm being pivotally connected with said cross bar so as to be foldable relatively 100 thereto, and means for holding each arm in its operative position relative to said cross bar, consisting of a clamping bolt mounted on the cross bar and adapted to engage with the respective arm. 105

7. A garment measuring device comprising an upright bar adapted to be engaged with the back of the person being measured, a horizontal cross bar adjustable vertically 110 on said upright bar and composed of sections adjustable horizontally relatively to each other, a double armed lever pivotally supported between its ends on said upright bar, and links connecting the arms of said lever with the opposite sections of said cross bar. 115

8. A garment measuring device comprising an upright bar adapted to engage with the back of the person being measured, a slide adjustable vertically on said upright bar, a horizontal cross bar having sections which are movable horizontally relatively 120 to each other on said slide, means for causing said cross bar sections to move in unison toward and from said upright bar consisting of an upright double armed lever pivotally supported on said slide, and links connecting the arms of said lever with opposite sections of said cross bar, and arms arranged on said 125

cross bar sections and adapted to engage the person being measured.

9. A garment measuring device comprising an upright bar adapted to engage with the back of the person being measured, a slide adjustable vertically on said upright bar, a horizontal cross bar having sections which are movable horizontally relatively to each other on said slide, means for causing 10 said cross bar sections to move in unison to-

ward and from said upright bar consisting of an upright double armed lever pivoted on said slide, and links connecting the arms of said lever with opposite sections of said cross bar, arms arranged on said cross bar sections and adapted to engage the person being measured, and means for holding said cross bar sections and slide in their adjusted position. 15

MORRIS W. GREENBERG.
